AMMONIUM NITRATE EXPLOSIVES

Leonard A. Stengel, Terre Haute, Ind., assignor to Commercial Solvents Corporation, New York, N.Y., a corporation of Maryland

No Drawing. Filed June 4, 1959, Ser. No. 819,530

7 Claims. (Cl. 52—14)

My invention relates to new ammonium nitrate compositions suitable for use as explosives and for making explosives containing ammonium nitrate and an amino compound represented by the structural formula

where R is selected from the group consisting of lower alkyl, lower hydroxyalkyl and $-C_2H_4NH_2$ and R' is selected from the group consisting of hydrogen, lower alkyl and $-C_2H_4NH_2$, and to processes for using same.

Ammonium nitrate has long been known to be flammable and explosive and these properties have been made use of extensively, ammonium nitrate being now widely used as an explosive although it possesses certain inherent disadvantages, such as low density, and relative insensitivity when used as an explosive.

While these low density ammonium nitrate explosives are satisfactory for certain situations involving relatively easy blasting, they cannot develop the detonation velocities and bore hole pressures needed in blasting hard rock difficult to fracture. The ammonium nitrate-amino compositions of my invention, however are of relatively high density ranging from 1.0 to 1.5 and are sufficiently sensitive for practical application in blasting without any manufacturing steps or ingredients not readily, simply and safely performed and used at the site. High density ammonium nitrate mixtures of this range used in the past have either involved a sensitizer more sensitive and dangerous to handle than the ammonium nitrate and hence such mixtures were difficult to store, ship, handle and mix with other ingredients or they involved manufacturing steps difficult to carry out in the field.

It is extremely dangerous to prepare ammonium nitrate explosives containing trinitrotoluene or other similar explosives outside of a permanent industrial explosives factory meeting all known safety requirements and operated by personnel experienced in the manufacture of explosives. Furthermore, the ammonium nitrate and carbonaceous material ordinarily used therewith must be thoroughly mixed and combined in equipment which is only found in an industrial plant for the manufacture of explosives. As large amounts of ammonium nitrate and sensitizers are always present in factory operations, there is the ever-present danger of disastrous explosions which may demolish the area surrounding the industrial plant for the production of explosives.

I have now discovered that combinations of ammonium

2

nitrate with varying amounts of amino compounds represented by the structural formula

where R is selected from the group consisting of lower alkyl, lower hydroxyalkyl, and $-C_2H_4NH_2$ and R' is selected from the group consisting of hydrogen, lower alkyl and $-C_2H_4NH_2$, ranging from 2 to 50% by weight, based on the weight of the mixture, can be advantageously employed either as explosives or in the preparation of explosives. Compositions containing the amino compounds hereinabove specified in amounts ranging from 2-14%, and preferably in amounts ranging from 6-8% by weight, based on the weight of the mixture, constitute effective explosives and are generally more effective as such than other previously known ammonium nitrate explosives. As the amount of said amino compounds is increased beyond the preferred ranges above specified the sensitivity of the compositions as explosives decreases. This property permits the formulation of ammonium nitrate-amino compound compositions of sufficiently reduced sensitivity to allow their transportation with safety. I prefer, therefore, to produce and ship compositions in solution form consisting of ammonium nitrate dissolved in 15-50% and preferably 20-50% by weight of said amino compounds, based on the weight of the mixture, and then at the site of use add to said solution additional ammonium nitrate to give a satisfactory slurry of ammonium nitrate-amino compound composition consisting essentially of ammonium nitrate and 2-14% by weight, and preferably 6-8%, of said amino compound, based on the weight of the mixture.

My new compositions suitable either for use as explosives or in the preparation of explosives consist essentially of a mixture of ammonium nitrate and the required amount of an amino compound represented by the structural formula

where R is selected from the group consisting of lower alkyl, lower hydroxyalkyl, and $-C_2H_4NH_2$, and R' is selected from the group consisting of hydrogen, lower alkyl and $-C_2H_4NH_2$. Examples of such amino compounds include primary and secondary amines, including di- and tri-primary amines, and amino alcohols containing 1-4 carbon atoms. Compounds of this type include mono- and di-methyl-, ethyl-, propyl-, isopropyl-, n-butyl-, secondary butyl-, and isobutyl-amines, ethylene diamine, diethylene triamine, monoethanolamine, mono-propanolamine, butanolamine, 2-amino-1-butanol, etc. Solutions of ammonium nitrate in these amino compounds are preferably first prepared by thoroughly mixing the ammonium nitrate with the required amount of amino compound, 20-50% by weight of amino compound, based on the weight of the mixture, ordinarily being required. I can then continue the addition of ammonium nitrate to give an explosive composition in the form of a slurry or wet solid containing amino compound in the range of 2-14% by weight of amino compound, and preferably

6-8%, based on the weight of the mixture. I prefer, however, to transport the ammonium nitrate-amino compound composition of reduced sensitivity in solution form to the site of use before adding the additional ammonium nitrate.

The ammonium nitrate utilized in my invention for explosives is preferably essentially anhydrous pure ammonium nitrate or fertilizer grade ammonium nitrate, either uncoated or coated with various coating agents, such as resin, diatomaceous earth, etc. Pure anhydrous ammonium nitrate is preferred. The amino compound such as, for example, the monomethylamine or dimethylamine, used in my invention is also preferably anhydrous. When the ammonium nitrate and sufficient quantity of the amino compound are brought into contact a solution ordinarily quickly forms. My solutions are preferably formed by adding the amine in the liquid state to the ammonium nitrate. If added in gaseous form, it is generally necessary to provide means for cooling to prevent excessive solution temperatures.

The bulk density of granular ammonium nitrate of the grade ordinarily used for explosive purposes is approximately 0.90-1.01. By adding 7.0-8.0% by weight of the monomethylamine, based on the weight of the mixture, to the same grade ammonium nitrate, the bulk density of the ammonium nitrate is increased to approximately 1.5. This increase in bulk density materially increases the effective explosiveness of the charge. In mining operations, in particular, the requirement for smaller or fewer bore holes for a given charge materially reduces drilling costs.

My new compositions containing ammonium nitrate as the essential explosive ingredient are not subjected to the hazards in production and handling present in the use of previously known explosives containing ammonium nitrate by reason of the fact that they can be easily and simply prepared at the site at which they are to be used. In many instances, the explosives can be prepared directly in the bore hole by simply placing the ammonium nitrate charge in the bore hole and by passing a suitable amount of the said amino compound in gaseous or liquid form through the ammonium nitrate therein. Alternately, ammonium nitrate can be placed in the bore hole and an amount of a solution of ammonium nitrate in said amino compound sufficient to give a final ammonium nitrate-amino compound composition of the desired composition and degree of sensitivity added thereto.

My new explosive compositions can also be prepared in the bore hole by dissolving the said amino compound in a liquid in which it is soluble, such as ethanol when monomethylamine is used as the amino compound, and pouring the resulting amine solution over the ammonium nitrate charge previously placed in the bore hole. The charge can, of course, include carbon black, ground coal, morpholine, lower alkyl alcohols, dimethylformamide, dimethyl sulfide, aluminum, sulfur, ferrosilicon, paraffin wax, resin, or other ingredients ordinarily incorporated into ammonium nitrate explosive compositions. The ammonium nitrate-amino compound compositions of my invention require primer charges to initiate and propagate detonation waves through the charge. If the bore hole in which the explosive is to be detonated is wet, horizontal, or slanting, the ammonium nitrate can be placed in a container such as a polyethylene bag or metal cartridge and the amino compound or ammonium nitrate-amino compound solution introduced into the container or cartridge just prior to its insertion in the bore hole. In this manner, the hazards of mixing and transporting the finished explosive compositions are avoided. It should be noted that the incorporation of the amino compound into the ammonium nitrate mixture, or the incorporation of an amount thereof to give compositions containing the amino compound in amounts ranging from 2-14% at the site of usage reduces the necessity of pre-

paring large amounts of a sensitive explosive at any one place, and thereby materially reduces the hazard to life and health of the personnel working in the area.

While my new explosive compositions consist essentially of ammonium nitrate and said amino compounds, they may also include varying amounts of different additives of the character customarily used in explosive compositions; such as compositions which increase or reduce the desired explosive properties of the mixture, or which sensitize or desensitize them. Other additives include compounds which add oxidizing or reducing potentials to the explosive compositions, or which catalyze the burning rate thereof, or which reduce the freezing points of the compositions when transported in solution form. Fuels which I have found to be useful in my explosives include ammonia; metals, aluminum or magnesium; petroleum fractions, wood flour; carbon black; alcohols, such as methanol or ethanol; etc.

The sensitivity and general utility of my new ammonium nitrate-amino compound compositions as explosives will vary slightly with the particular amino compound employed as well as the amount thereof. The effectiveness of an explosive mixture containing 7.95% by weight of monomethylamine as compared to a number of commercial explosives, using nitroglycerine as a standard, is shown in the following table.

TABLE I

Composition	Loading Density, gms./cc.	Ratio, Rate of Detonation	Ratio, Detonation Temp.	Ratio, Detonation Press.	Ratio, Work of Adiabatic Expansion
Nitroglycerine	1.60	1.00	1.000	1.000	1.000
50% Ammonia dynamite ¹	1.50	0.83	0.770	0.706	0.859
Ammonium Nitrate-monomethylamine	1.45	0.74	0.566	0.548	0.678
10% Ammonia dynamite	0.98	0.521	0.555	0.228	0.641
Akremite ²	0.80	0.445	0.525	0.147	0.585

¹ 50% nitroglycerine gelatin dynamite containing ammonium nitrate

² An explosive containing approximately 92% ammonium nitrate and 8% carbon black.

From the above data, it will be seen that the explosives of my invention are comparable in effectiveness with 50% ammonia dynamite. My explosives, however, are decidedly less expensive and more much more safely handled than the latter, due to the fact that the explosives of my invention can be prepared at the site of usage as required and in amounts needed and do not require the shipping, storage and handling precautions required for previous types of explosives.

While the explosive compositions of my invention containing as little as 2% of said amino compounds are sensitized to some extent, about 5-10% of amino compound such as monomethylamine is required to produce maximum sensitivity. While my ammonium nitrate-amino compound compositions are not cap sensitive, they have high sensitivity for a mixture of such high density; i.e., a 92.1% by weight ammonium nitrate-7.9% monomethylamine mixture was found to require only a 70 g. pressed tetryl booster to completely detonate a column of explosive having a length of 28 inches and a diameter of 7 inches. The liquid compositions of my invention containing from about 15-50% amino compound have the same order of sensitivity as pure ammonium nitrate at sea level pressure.

The following table shows the use of a representative group of additives in my ammonium nitrate explosives prepared with monomethylamine, using different ratios of ammonium nitrate and monomethylamine which I have found to give effective explosives.

5
TABLE II

Fuel	Percent	Mono-methyl-amine	Ammonium Nitrate, Percent
Coal Dust	7	3	0
Wheat Flour	7	2	91
Wood (Powdered)	8	2	90
Carbon Black	7	3	90
Ammonia	6	2	92
		6	94
		25	75

The following table sets out some of the physical properties of ammonium nitrate-monomethylamine explosive compositions.

TABLE III

Physical properties of ammonium nitrate-mono- and di-methylamine solutions

Percent Wt. Monomethylamine	18.1	27.1

40° C	1.170	

A practical method of producing a satisfactory explosive composition from ammonium nitrate and dimethylamine is carried out as follows: A tin can 7½ inches I.D. by 24 inches long is filled with dry granular high density ammonium nitrate and then a solution of ammonium nitrate in dimethylamine (75% by weight ammonium nitrate-25% by weight dimethylamine) is added so as to fill all of the voids, using a ratio of 0.4 pound of solution to 1.0 pound of granular ammonium nitrate. The resulting composition consists approximately 92% ammonium nitrate and 7% dimethylamine.

The use of my new ammonium nitrate-amino compound explosive compositions is illustrated by the following examples.

EXAMPLE I

Four deep bore holes were drilled in a row into a strata of hard rock overburden containing seams of taconite found to be particularly difficult to drill and blast 35 feet deep. These holes were charged with 40 pound cans of explosives. Each can, 7¾ inches diameter by 16 inches long, was charged with a composition consisting of ammonium nitrate and dimethylamine in the ratio of one pound of ammonium nitrate to 0.39 pound of a composition consisting of 75.87% ammonium nitrate and 24.13% by weight of dimethylamine. Ten of these cans were placed in each of two of the bore holes and nine cans were placed in each of the other two bore holes. A 6½ inch diameter Nitramite primer (Du Pont, weight 9 pounds) was placed in the middle of the charges (above the fifth can) and a second Nitramite primer was placed under the top can. A single line of Primacord was run to the two primers. All of the holes contained con-

siderable water and water ran out of the top of the first hole when it was tamped. After firing, the entire point where the bore holes were located had raised up and slid forward forming a crater approximately 6 feet across by 15 feet long and 10 feet deep nearly 24 feet beyond the furthest bore hole. Earth cracks extended a considerable distance beyond the crater. While some of the surface rock was in large pieces, there appeared to be nothing that could not be handled by a shovel.

EXAMPLE II

Liquid monomethylamine was added to ammonium nitrate in comminuted form in an amount sufficient to give a solution of the ammonium nitrate in the monomethylamine. The resulting composition contained 79.56% ammonium nitrate and 20.44% monomethylamine. Commercial coated ammonium nitrate was then mixed with this solution in the ratio of 0.614 pound of solution to 1 pound of ammonium nitrate. A quart size tin can was filled with this slurry which consisted of 90.36% by weight of ammonium nitrate, 7.78% by weight of monomethylamine and 1.85% by weight inert (coating agent). The filled can then was buried in soil so that the top of the can was level with the surface of the ground. Two 37 gram blocks of Pentolite booster explosive were taped to the top of the can. Two No. 8 electric dynamite caps were pressed into holes in the Pentolite blocks. The caps were then detonated, initiating detonation of the Pentolite and the latter in turn initiating the ammonium nitrate-monomethylamine compositions. A crater which was about 72 inches in diameter and 20 inches deep was formed. A comparison test in which the same type Pentolite booster was taped to a quart can filled with water produced only a slight depression in the soil about 16 inches in diameter by 7 inches deep.

This application is a continuation-in-part of my U.S. patent application Serial No. 681,437, filed September 3, 1957, and U.S. Serial No. 735,987, filed May 19, 1958.

Now having described by invention, what I claim is:

40 1. Ammonium nitrate compositions suitable for use in the explosive art consisting essentially of mixtures of ammonium nitrate with 2-50% by weight, based on the weight of the mixture, of an amine having the structural formula

50 where R is selected from the group consisting of lower alkyl, lower hydroxyalkyl and $-C_2H_4NH_2$, and R' is selected from the group consisting of hydrogen, lower alkyl and $-C_2H_4NH_2$.

55 2. Ammonium nitrate compositions suitable for use as explosives consisting essentially of mixtures of ammonium nitrate with 2-14% by weight, based on the weight of the mixture, of an amine having the structural formula

60 where R is selected from the group consisting of lower alkyl, lower hydroxyalkyl and $-C_2H_4NH_2$, and R' is selected from the group consisting of hydrogen, lower alkyl and $-C_2H_4NH_2$.

65 3. Ammonium nitrate compositions suitable for use in producing explosives consisting essentially of mixtures of ammonium nitrate with 20-50% by weight, based on the weight of the mixture, of an amine having the structural formula

where R is selected from the group consisting of lower alkyl, lower hydroxyalkyl and $-C_2H_4NH_2$, and R' is selected from the group consisting of hydrogen, lower alkyl and $-C_2H_4NH_2$.

4. Ammonium nitrate compositions suitable for use as explosives consisting essentially of mixtures of ammonium nitrate and 2-14% by weight, based on the weight of the mixture, of monomethylamine.

5. Ammonium nitrate compositions suitable for use as explosives consisting essentially of mixtures of ammonium nitrate and 2-14% by weight, based on the weight of the mixture, of dimethylamine.

6. Ammonium nitrate compositions suitable for use in producing explosives consisting essentially of mixtures of ammonium nitrate with 20-50% of monomethylamine, based on the weight of the mixture.

7. Ammonium nitrate compositions suitable for use in producing explosives consisting essentially of mixtures of ammonium nitrate with 20-50% of dimethylamine, based on the weight of the mixture.
